(57) **CLAIM**

The ornamental design for a video conference panel lighting fascia, as shown and described.

DESCRIPTION

FIG. 1 is a front perspective view of a video conference panel lighting fascia;

FIG. 2 is a front elevation view of the video conference panel lighting fascia of FIG. 1;

FIG. 3 is a rear elevation view of the video conference panel lighting fascia of FIG. 1;

FIG. 4 is a top plan view of the video conference panel lighting fascia of FIG. 1;

FIG. 5 is a bottom plan view of the video conference panel lighting fascia of FIG. 1;

FIG. 6 is a first side elevation view of the video conference panel lighting fascia of FIG. 1;

FIG. 7 is a second side elevation view of the video conference panel lighting fascia of FIG. 1; and,

FIG. 8 is a front perspective view of the video conference panel lighting fascia of FIG. 1 incorporated into a video conference panel.

In the drawings, the broken lines depict environmental subject matter only and form no part of the claimed design.

1 Claim, 5 Drawing Sheets
